(No Model.)

T. G. BENNETT.

MEANS FOR SEPARABLY UNITING BARRELS TO STOCKS OF GUNS.

No. 487,465.

Patented Dec. 6, 1892.

UNITED STATES PATENT OFFICE.

THOMAS G. BENNETT, OF NEW HAVEN, CONNECTICUT, ASSIGNOR TO THE
WINCHESTER REPEATING ARMS COMPANY, OF SAME PLACE.

MEANS FOR SEPARABLY UNITING BARRELS TO STOCKS OF GUNS.

SPECIFICATION forming part of Letters Patent No. 487,465, dated December 6, 1892.

Application filed April 4, 1892. Serial No. 427,782. (No model.)

To all whom it may concern:

Be it known that I, THOMAS G. BENNETT, of New Haven, in the county of New Haven and State of Connecticut, have invented a new Improvement in Firearms; and I do hereby declare the following, when taken in connection with the accompanying drawings and the letters of reference marked thereon, to be a full, clear, and exact description of the same, and which said drawings constitute part of this specification, and represent, in—

Figure 1, a side view of the receiver of the arm, showing the portion of the barrel and magazine and also a portion of the stock; Fig. 2, a transverse section on line $x-x$ of Fig. 1, looking rearward; Fig. 3, an under side view of the receiver; Fig. 4, the rear portion of the receiver and its part of the stock detached; Fig. 5, the forward part of the receiver detached; Fig. 6, a longitudinal section cutting on line $x-x$ of Fig. 3; Fig. 7, a modification.

This invention relates to an improvement in firearms in which the barrel opens into the receiver at the rear applicable also to arms in which a magazine is arranged beneath the barrel, the object of the invention being to construct the arm so that the barrel may be readily separated from the stock for the convenience of packing, transportation, or for any purpose for which it may be desirable to detach the barrel from the stock; and the invention consists in the construction, as hereinafter described, and particularly recited in the claims.

In illustrating the invention it is shown as applied to a receiver, such as employed in the well-known Winchester repeating-gun.

A represents the receiver, to the forward end of which the barrel B is attached in the usual manner, and as here represented the magazine C is arranged beneath the barrel. Both the barrel and magazine open at the rear into the receiver. The receiver is constructed in two parts, the two sides or cheeks D D being made as a part of the extreme forward end of the receiver, to which the barrel is attached. The other part E forms the rear end of the receiver and is attached to the stock. From this part E an arm F projects forward, which forms the bottom of the re-

ceiver and is adapted to stand between the two sides D D at the rear and the part E, which is attached to the stock, are constructed to abut together, as seen in Fig. 1. The arm F is constructed with a longitudinal rib G upon each side, and the two sides D D are constructed with corresponding longitudinal grooves (see Fig. 2) and so that the forward part of the receiver may slide onto the rear part, the ribs G running into the grooves of the sides until the two parts abut together at the rear. The ribs firmly interlock the two parts so as to prevent vertical movement.

The two parts together are securely locked to prevent their longitudinal movement. As here represented this is accomplished by means of a swinging lever H, hung in the arm F upon a horizontal axis, and so as to swing in a vertical plane, as from the position seen in Fig. 1 to that shown in broken lines in the same figure, and also shown in Fig. 4. The lever is provided with a suitable handle J by which it may be conveniently operated. On the outer side of the lever H is a rib K, and the corresponding side of the receiver is constructed with a groove L, corresponding to the rib K, and so that when the two parts are set together and the lever turned to the position seen in Fig. 1 and also seen in Fig. 3 the rib K enters the groove L in the side D of the receiver, and as the lever is hung to the arm F, so as to make firm engagement therewith, the rib of the lever serves to interlock the forward part of the receiver with the rear part, and so as to prevent possible longitudinal movement. The rib and groove are constructed so as to produce a cam-like action, that the entrance of the rib into the groove may tend to draw the two parts close together.

A spring M is arranged in the arm F so as to bear upon the pintle N of the lever H, and one side of this lever is flattened, as at O, and so that when the lever is turned to the locking position this spring will rest upon the flat surface O and yieldingly hold the lever in the closed position, and so that as the lever is turned toward the open position the pintle N will operate as a cam to raise the spring.

To separate the two parts, so as to readily

detach the barrel and the forward part of the receiver from the stock and rear portion of the receiver, it is only necessary to turn the lever away from its locked position, as indicated in broken lines, Fig. 1, and then withdraw the barrel and the forward part of the receiver from the stock, and to replace the two parts requires simply a reverse operation.

It will be understood that the longitudinal ribs on the rear part of the receiver and the grooves in the forward part may be reversed—that is to say, the ribs may be on the sides of the forward part of the receiver and the grooves in the rear portion, such modification being too apparent to require illustration.

Instead of the locking device hereinbefore described a screw or pin may be introduced transversely through the two sides and through the arm F, as seen in Fig. 7. The removal of the screw or pin will permit the separation of the two parts.

The modification of the locking device seen in Fig. 7 is sufficient to indicate that any suitable locking device between the two parts may be employed. Again, the locking device, instead of being hung to the rear portion of the receiver and so as to engage with the forward portion, may be hung in the forward part of the receiver, so as to engage with the rear portion—a modification also too apparent to require illustration.

The illustration and description of this invention as applied to the Winchester arm will be sufficient to enable those skilled in the art to apply the invention to other constructions of the receiver. The invention is not therefore to be limited to any construction of receiver.

I claim—

1. In a firearm, a receiver having a barrel attached to the forward end of the receiver, the receiver constructed in two parts, the forward part carrying the two sides and barrel, the rear part carrying the stock, the said rear part constructed with a forwardly-projecting arm adapted to removably set between the two sides of the forward part of the receiver and the two sides adapted to abut against the rear portion of the receiver, the one part constructed with longitudinal ribs and the other with corresponding longitudinal grooves, and a locking device substantially such as described between the two parts, whereby they may be detachably secured when set together, substantially as specified.

2. A receiver for firearms, made in two parts, the forward arm carrying the barrel and the two sides of the receiver, the rear part carrying the stock and constructed with an arm projecting forward, adapted to set between the two sides and form the bottom of the receiver, means, substantially such as described, to interlock the two parts against vertical movement, a swinging lever arranged upon a transverse axis in one part near the forward end, the said lever constructed with a rib and the other part constructed with a groove corresponding to said rib on the lever, and whereby the said two parts may be interlocked against longitudinal movement, substantially as specified.

In testimony whereof I have signed this specification in the presence of two subscribing witnesses.

THOMAS G. BENNETT.
